UNITED STATES PATENT OFFICE.

JOHN T. HORTON, OF BROOKLYN, NEW YORK.

DESIGN FOR AN INSULATOR.

52,991.

Specification for Design.

Patented Feb. 11, 1919.

Application filed September 7, 1917. Serial No. 190,279. Term of patent 14 years.

To all whom it may concern:

Be it known that I, JOHN T. HORTON, a citizen of the United States, residing at New York, borough of Brooklyn, in the county of Kings and State of New York, have invented a new, original, and ornamental Design for Insulators, of which the following is a specification, reference being had to the accompanying drawing, forming part thereof, wherein Figures 1, 2, and 3 are a bottom plan view, a front elevation, and an end elevation, respectively, of an insulator showing my new design.

I claim:

The ornamental design for an insulator as shown.

Signed at New York, in the county and State of New York, this 4 day of Sept., 1917, before two subscribing witnesses.

JOHN T. HORTON.

Witnesses:

WILBUR M. STONE,
CHAS. W. LA RUE.
